SWITCH MECHANISM WITH WIRE
ARMATUREClarence C. Rennecamp, St. Louis, Mo., assignor,
by mesne assignments, to Missouri Automatic
Control Corporation, a corporation of Missouri

Application December 4, 1946, Serial No. 713,967

2 Claims. (Cl. 175—345)

1

This invention relates to switch mechanisms and more particularly to switch mechanisms actuated by temperature or pressure responsive devices and including magnetic means which acts to provide a snap action in both closing and opening movements of the switch.

In mechanisms of this character the relationship of the armature to the magnet when in an attracted position is extremely critical because it determines the minimum differential in a condition which will cause the switch to be moved from an open to a closed position and vice versa.

In the usual construction of armatures of this type in which flat surfaces of extended area are presented to a flat surface of the magnet, any slight non-parallelism or irregularity of the surfaces occurring in manufacture, assembly or in adjustment will alter the magnetic pull and therefore the differential.

Because any variables due to such surface irregularities or non-parallelism are greatly multiplied as the distance between armature and magnet are decreased, it is customary to provide stops for definitely spacing the armature from the magnet when in its attracted position.

It is an object of the present invention to provide a new and improved switch mechanism adapted to economical and uniform manufacture.

A further object is to provide a switch mechanism incorporating an improved two direction magnetic snap action device having substantially point contact between magnet and armature.

A further object is to provide a novel and improved armature having a pair of substantially spherical contacting surfaces spaced from the center of mass of the armature and arranged to alternately contact the magnet.

Other objects and advantages will appear in the following description and accompanying drawing referring to which:

Fig. 1 is a front view of a switch mechanism constructed in accordance with the present invention.

Fig. 2 is a longitudinal section taken on line 2—2 of Fig. 1.

Fig. 3 is a transverse section taken on line 3—3 of Fig. 1.

Figs. 4, 5 and 6 are enlarged detail views of the armature.

In the drawing reference numeral 10 indicates a channel shaped frame member having attached thereto front plate members 11 and 12.

The front plate members are attached to the channel frame by the four peened over projections 13. Plate member 11 is of insulating mate-

2

rial and has mounted thereon switch terminal connectors 14 and 15. The connectors have riveted thereto flexible switch blades 16 and 17 respectively, which in turn carry contacts 18 and 19 respectively. A cover 20 fits over the frame 10, its open side resting against the front plate members 11 and 12.

Pivoted on a pin 21 which is supported in the side walls of frame member 10 are a differential lever 22 and a primary lever 23. Lever 22 has a forked outer end 24 extending between a fixed stop 25 and the adjustable collar 26 on the threaded member 27. Lever 22 is further provided with a right angularly formed portion 28. Lever 23 also has a right angularly formed portion 29 at its outer end. Lever 23 is urged in a clockwise direction by actuation spring 30.

A secondary lever generally indicated at 31 is provided at one end with right angularly formed portions 32 and 33 parallel to the formed portions 28 and 29 of levers 22 and 23. Lever 31 is connected to levers 22 and 23 by thin flexible strips 34 and 35. These strips 34 and 35 perform the function of pivoted links and have the advantage of eliminating any lost motion incident to the necessary tolerance in fitting and journaling link pivots. Lever 31 includes an intermediate portion 36 of insulating material and a flexible free end portion 36a.

Lever 31 carries at its free end, an armature generally indicated at 37, preferably formed of round wire of magnetic material and having the general shape of a block letter S. A loop 38 formed at the end of the upper horizontal leg 35 facilitates suitable attachment to the outer end of lever 31 by a bolt 39. A bar magnet 40 supported in an insulator block 41 has one end projecting between the intermediate and lower horizontal legs 42 and 43 of the armature. The magnet supporting block 41 is attached to the base of frame 10 by inserted rivets 44.

In order to space the main mass of legs 42 and 43 from the magnet when either are in the attracted position, and in order to provide a flux path between the main mass of the armature legs and the magnet, a pair of inwardly formed V-shaped projections 45 and 46 are provided. The points of the V's, 45 and 46 are rounded with a radius approximately equal to the diameter of the wire, resulting in a substantially spherical point.

Lever 31 also carries at the outer end of its insulator section 36 a screw 47 which under certain conditions bears against the outer end of

switch blade 17 thereby to open the contacts 18 and 19.

There is a stud 48 extending thru an opening 49 in lever 23, an opening 50 in lever 22, and an opening 51 in the base of frame 10. Stud 48 threadedly engages an adjusting nut 52 at one end and at its opposite end abuts the displaceable wall or diaphragm 53 of a solid charge type condition responsive element generally indicated at 54. Element 54 further includes a rigid cup shaped member 55 having a flange 56 and a capillary tube 57 which communicates with a bulb (not shown) located in the conditioned area. Element 54 is securely fastened to the base of frame 10 by screws 58. Cover member 20 and a mounting bracket 59 (shown in part) are also secured to the base of frame 10 by screws 58.

Adjusting nut 52 is guided for free axial and rotary movement in a washer 59 which is mounted in front plate 12. The outer end of nut 52 has an indicator dial 60 attached thereto and a spring 61 having one end bearing against the end of stud 48 and its other end bearing against the nut 52 thru an intermediate washer 62 provides increased friction for retaining adjusted positions. The opposite or inner end of nut 52 engages a pair of projections 63 on the primary lever 23.

A return spring 64 having one end bearing against the base of frame 10 and its other end against a collar 65 on stud 48 normally urges the stud and nut 52 toward the left (in the drawing) and therefore urges lever 23 in a counterclockwise direction. Spring 64 is sufficiently stronger than spring 30 to readily overcome it.

Operation

The switch mechanism shown in the drawings operates upon an increase in temperature or expansion of the solid liquid charge in the element 54 to close a circuit, as would be required in refrigeration service wherein the closing of contacts 18 and 19 would complete an energizing circuit for a compressor or the like. It will be noted however, that by simply switching the connections of the levers so that angularly formed portion 33 of lever 31 is connected to lever 23 at 29 and portion 32 is connected to lever 22 at 28 instead of the way shown, the mechanism would then operate to open a circuit upon an increase of temperature as would be required for a space heating control.

As shown in the drawings the mechanism is in a circuit closing position, to which it is moved under the urging of spring 30 upon sufficient expansion of element 54. The outer end of arm 31 is in its leftwardmost position, Fig. 2, screw 47 having been moved leftward sufficiently to permit the closing of contacts 18 and 19 by the spring action of switch blade 17. The outer end of lever 22 bears against the collar 26 of differential adjusting screw 27 and horizontal leg 42 of the armature 31 is in contact with magnet 40 thereby holding the outer end of arm 31 by magnetic force.

Upon a decrease in temperature resulting in a contraction of the solid liquid charge, return spring 64 will act to cause stud 48 and nut 52 to move leftward following the movement of diaphragm 53. This movement will cause a counterclockwise rotation of lever 23 about its pivot 21, and it will carry with it the connected end of lever 31 and therefore the outer end of lever 22 until the outer end of lever 22 abuts the fixed

stop 25 which is the limit of the adjustable lost-motion differential.

During this first phase of the switch opening movement, that is until the outer end of lever 22 abuts the stop 25, the lever 31 pivots about the ball point of armature leg 42. Continued decrease in temperature and therefore further counterclockwise rotation of lever 23 after contact has been made with stop 25 will cause the connector strip 35 to flex, and as a result the outer free end of lever 31, to swing toward the right. During this latter phase of the opening movement, however, and until a critical point is reached wherein the magnetic attraction of leg 42 of the armature is overcome, it will be seen that energy is stored in the flexible outer end portion 36a of lever 31. This energy initiates a snap action of the outer end of arm 31 in a rightwardly direction and provides a carry over to the point where leg 43 of the armature is moved into a sufficiently strong magnetic field to complete the opening movement.

It is desirable in many types of service that the mechanism operate from a switch open to switch closed position upon a very slight change in temperature, often as slight a differential as 2° F. In the mechanism shown the resulting movement of stud 48 due to volume change of the solid liquid charge for a temperature change of 2° F., would be between one and two thousandths (.001 and .002) of an inch. With this in view it will be readily appreciated that even slight variations in the magnet and armature relationship from unit to unit will appreciably affect the uniformity of manufacture with respect to minimum operating differential.

In the armature construction shown, slight lateral or longitudinal tilting with respect to the face of the magnet is not reflected in any measurable variation of operating differential. In this construction there is provided a rounded point contact between armature and magnet and a means for spacing the main mass of the magnet from the main mass of the armature which lends itself admirably to uniform and economical manufacture. This spacing means being of magnetic material provides a flux path between the main mass of the armature and the magnet.

Obviously, numerous modifications of the principles of this invention will occur to those skilled in the art. For example, the magnet itself may be provided with projections having ends with reduced area for contact with flat surfaces of an armature.

The exclusive use of all such modifications within the scope of the appended claims is contemplated.

I claim:

1. For use in a device of the class described, a movable armature constructed of round wire and having a portion thereof formed in a general U shape a bar magnet disposed between the parallel legs of said U-shaped portion, each of said parallel legs having an inwardly formed V-shaped projection adapted to contact said magnet as said armature legs are alternately moved toward it, whereby the main mass of said armature portions are spaced from said magnet and whereby substantially point contact is made.

2. For use in a device of the class described, a movable armature constructed of round wire having the general form of a block letter S, a bar magnet disposed between the lower horizontal legs of said armature, the upper horizontal leg of said armature having an attaching eye formed

at its open end, and each of said lower horizontal legs having a portion formed in a general V-shape with its apex toward said magnet, whereby substantially point contact is made between said magnet and said armature as the lower horizontal legs thereof are alternately moved toward said magnet.
